ATTORNEYS

UNITED STATES PATENT OFFICE.

JAMES FRED ROBBINS, OF LINCOLN, ILLINOIS.

APPARATUS FOR SUPPLYING STEAM TO STEAM TABLES.

Application filed May 4, 1926. Serial No. 106,712.

My invention is an improved means for supplying steam for steam-tables, dish-washers, dish-dryers, and other apparatus requiring the use of steam; said means in the present 5 instance including a steam collecting tank with automatic water-supply tank, pipe connections, etc., whereby steam may be supplied for various uses by an economical use of heat from a range or other heater to effect a material saving in the running of an establishment such as a restaurant; to produce a type 10 of apparatus in which the water level in the steam collecting tank is maintained by an automatic water-supply tank alongside of the same instead of placing the float-valve and 15 float within the boiler.

My present invention therefore consists in the particular construction and arrangement of parts, all as hereinafter fully described and 20 specifically set forth in the appended claim.

In the accompanying drawings:

Figure 1 is a front elevation showing my improved apparatus for producing low-pressure steam for a steam-table.

Fig. 2 is a sectional view illustrating a modification in the shape and position of the water-supply tank, and boiler.

In providing the present type of apparatus the steam collecting tank 10 has the head 11 secured in place by bolts or screws so that it 30 may be readily and conveniently removed for the purpose of cleaning out the steam collecting tank and has the water inlet pipe passing through the center thereof, with the float operated valve to maintain the desired water level in said steam collecting tank located in a separate tank, hereinafter described. The steam collecting tank is of a convenient size for required steam capacity and so that it may 40 be supported for operation in connection with a water-heater, and when used with a range, A, it may be supported on the ledge *a* thereof, but it will be understood that in addition to being useable in connection with a range burning 45 coal, coke or other fuel it may be as conveniently and effectively operated in connection with any other heating device, as gas heaters, &c. Extending from the bottom of the steam collecting tank to a waterback or coil in the heating unit, as range A, are pipe connections 13 and 14 provided with valves 13^a 14^a, respectively, and also a short pipe 15 having a cock 15^a by means of which the steam collecting tank may be drained for cleaning 50 or the hot-water drawn off at any time for use. Furthermore, the steam collecting tank

is provided with water-gauge 17, blow-off valve 18, and steam-gauge 19, each being of conventional type with the blow-off valve and steam-gauge connected to the steam-supply 60 pipe 20 leading to the apparatus utilizing the steam produced in the steam collecting tank, said pipe being shown in the drawings as connected to a steam-table 21 as an example of the application of my invention and from 65 which extends return pipe 22. The supply pipe and return pipe may each have one or more cut-off valves, designated by the numerals 20^a and 22^a, and the return pipe provided with a steam trap 23. The supply pipe 70 20 may discharge the steam into a steam-table, dish dryer, or other apparatus, or it may connect with a coil in the steam-table or other apparatus. In this form of my invention a predetermined water level is maintained in the steam collecting tank by an 75 automatic water supply tank independent of the steam collecting tank, that is separate therefrom and located adjoining the head 11 thereof through which the pipe connections 80 26 and 27 between water tank and steam collecting tank pass, each of said pipe connections 26 and 27 including a union 26^a and valve 27, pipe 26 connecting with steam space in steam collecting tank and pipe 27 with the 85 lower part or water space in water tank and steam collecting tank, it being understood that the steam collecting tank and water tank are substantially on a line with each other. A 90 normal water level in the tanks and steam collecting tank is provided for by an automatic water supply valve 28, located in the water supply tank and connected to the water supply pipe similar to that illustrated at 61 in Fig. 2 which is provided with a cut-off 30 adjacent the tank and at a point beyond is connected by pipe 31 and valve 32 to pipe 13 extending from the steam collecting tank to the water back or heating-coil; this arrangement 95 of the pipe connections and valves being for the particular purpose hereinafter explained. The automatic water-supply valve is of a conventional type operated by float similar to that illustrated at 62 in Figure 2, and of course may be adjusted for the desired water level 100 leaving steam space in the upper part of each tank. The water-supply tank may be provided with a drain-cock 34 tapped in the bottom thereof, and with a blow-off valve 35 in the removable top, if desired.

The arrangement shown in Fig. 1 and hereinbefore described illustrates the preferred

form of my invention, and the same purposes may be obtained by the form or type of device shown in Fig. 2, in which I provide a vertical steam collecting tank 40, supported 5 on a standard 41 with a three-way coupling 42 having pipe connection 43 to bottom of steam collecting tank, pipe connection 44 to water-back or coil of the water-heater, as a range, &c., and a pipe-connection 45 to water-supply pipe 46; said pipe connection 45 having a cut-off valve 45^a, and the three-way coupling 42 provided with a draw-off cock 47. The steam collecting tank is provided with a water-gage 48, pipe-connection 49 forming 10 the return from water-back or heating-coil, and from the top extends a steam-supply pipe 50 leading to the steam-table, dish-dryer, or other apparatus using the steam, said steam-supply pipe having blow-off valve 51 15 and steam-gage 52. The water-tank 53 used in connection with this steam collecting tank is preferably arranged horizontally, as shown, and is also tapered, with the pipe connections 54 and 55 extending into the upper 20 and lower ends of the wider portion of the tank, said pipe-connections each having a union 56 and cut-off valve 57. The tank is supplied with water from the water-supply pipe 46 by a pipe connection 58 having a 25 cut-off valve 59, said pipe connection 58 passing through the outer end of the removable head 60 of the tank to an automatic valve 61 having float 62.

It will be noted that in each instance (Figs. 30 1 and 2) the float-valve can be examined for repair, etc., or the tank supplying the water to steam collecting tank cleaned out without putting out the fire in a range to which said tank is connected; this being done by simply 35 closing the valves in pipe connections between water supply tank and steam collecting tank, then closing valve in pipe connection between tank and water-supply pipe, and opening the valve in pipe connection between 40 water-supply pipe and bottom of the steam collecting tank; for instance in Fig. 2 by closing valves 57 to cut off communication of 45 water and steam from steam collecting tank,

closing valve 59 to cut off the supply of water to the water supply tank, and opening valve 45^a so that water may be supplied directly 50 to the bottom of the steam collecting tank and water-back or heating-coil by way of the coupling 42; it being understood of course 55 that when the water is being supplied to the steam collecting tank from the automatic tank valve 45^a is closed and valves 57, 57, and 59 open. It will also be readily understood 60 that in the operation of the steam collecting tank it will require no special attention inasmuch as the water is supplied thereto and water-level therein maintained by the automatic supply tank, for if the steam pressure should become too high the pressure would be lowered by exhaust through blow-off valve 65 18, 51. The steam accumulating in the space at the upper part of the steam collecting tank is carried away by the steam supply pipe to the steam-table, or wherever it is needed, for 70 a dish-dryer, &c., as I propose to use the apparatus for many different purposes, the arrangement providing an economical steam-generating unit compact in construction and 75 effective in operation by which a circulation of low pressure steam giving the required heat for a steam table is furnished from the heat of a cooking range to save the expense of running a steam-boiler.

I claim:—

In combination with a cooking range 80 having a waterback, a steam table and means for supplying steam to the latter, comprising a steam collecting tank mounted a short distance above the top of the cooking range and having a valved outlet pipe depending from 85 the bottom thereof, pipe connections between the water back of the cooking range and the steam collecting tank, and pipe connections between said steam collecting tank and the steam table; together with a water tank also 90 located above the top of the cooking range and alongside of the steam collecting tank, and pipe connections between the water tank and steam collecting tank.

JAMES FRED ROBBINS.
